H. C. MITCHELL,
ORNAMENTING DEVICE AND METHOD,
APPLICATION FILED APR. 4, 1921,

1,422,599.

Patented July 11, 1922.

Harry Cecil Mitchell, ^{Inventor}
By *Frank S. Appelman*,
Attorney,

UNITED STATES PATENT OFFICE.

HARRY CECIL MITCHELL, OF YONKERS, NEW YORK.

ORNAMENTING DEVICE AND METHOD.

1,422,599.

Specification of Letters Patent. Patented July 11, 1922.

Application filed April 4, 1921. Serial No. 458,449.

To all whom it may concern:

Be it known that I, HARRY CECIL MITCHELL, a subject of the King of Great Britain, residing at Yonkers, in the county of Westchester and State of New York, have invented certain new and useful Improvements in Ornamenting Devices and Methods, of which the following is a specification.

This invention relates to ornamentation and particularly to the production of illustrations and pictures through the use of stencils which will deposit a pigment or coloring matter on a buffer or abrading pad which is rubbed on the stencil and over the object to be ornamented through the pattern or in interstices formed in the stencil.

It has been found in practice that a stencil cut in a body or sheet of tinfoil rubbed with a buffer can be made to mark paper or other objects and that the surfaces may be differently shaded to produce artistic effects. If the stencil is vigorously rubbed, the marking will be quite black, whereas lighter pressure on the buffer will result in reducing the density of the color, and by this means, shading effects may be produced.

It is a further object of this invention to produce a stencil of the character indicated which may be used for ornamenting paper and fabrics or the like, without the use of pigments or coloring matter except such as are inherent in the metal from which the stencil is made.

In carrying out the invention, I prefer to use tinfoil in sheets relatively heavy as compared with tinfoil ordinarily employed, and when a felt buffer is employed, it has been found that it becomes discolored from its application to the surface of the tinfoil, the density of the color being greater, in so far as operations have demonstrated, when felt is employed than when linen or silk material is rubbed on the surface of the tinfoil. Whether the increased deposit of the material of the tinfoil on the buffer is due to the fact that the abrading action of the wool is greater than the abrading action of the linen or silk, or whether it is due to the presence of oil in the wool, has not been determined, but in any event, a wool buffer is believed to be preferable and to produce more effective results.

It is a further object of this invention to produce buffers carrying pigments or coloring matter which impregnate the felt or fibres of the material of which the buffer is

formed, in order that when the buffer is rubbed over a stencil, it will deposit a coloring matter on the material being ornamented, and by this means, a comparatively inexpensive ornamenting outfit may be produced and one which can readily be handled without discoloring the hands of the user, or without liability of injuring materials or furniture which may be present when the device is being used, and therefore, it is believed to constitute a distinct advantage over those ornamenting processes which employ paint or granular pigments during the ornamenting process.

A further object of this invention is to produce an ornamenting outfit of the character indicated which is comparatively inexpensive and which can be operated by unskilled persons.

With the foregoing and other objects in view, the invention consists in the details of construction, and in the arrangement and combination of parts to be hereinafter more fully set forth and claimed.

In describing the invention in detail, reference will be had to the accompanying drawings forming part of this application where like characters denote corresponding parts in the several views, and in which—

Figure 1 illustrates a view in perspective of a stencil embodying the invention;

Figure 2 illustrates a perspective view of a buffer to be associated therewith; and

Figure 3 illustrates a plan view showing the effects attainable when carrying the invention into practice.

In these drawings 5 denotes a stencil which may have designs of any kind cut therein, and as stated, the material of which the stencil is formed is preferably sheet tinfoil or some equivalent material which can be abraded and caused to deposit a coloring agent on a buffer to be employed in conjunction with the stencil. The buffer 6 is preferably of wool, as stated, and when the stencil is applied to the material to be ornamented, the buffer is rubbed on the surface of the stencil until it becomes discolored, and thereafter, it is rubbed over that part of the stencil having the ornamentations in order that the discoloring agent carried by the buffer will be deposited on the material through the openings in the stencil. By rubbing portions of the surface to be ornamented in different degrees, shaded effects can be produced, and if stencils having figures cut

therein are employed and a picture is produced which is relatively black, and then the stencil is moved just a slight degree and the surface to be ornamented is colored more 5 lightly, it will give the effect of a shadow of the figure. In fact, the device is capable of other uses to produce different results, and the inventor does not wish to be limited with respect to its employment. The ornamenting 10 device can be employed as an amusement or an advertising feature, and it has many advantages over those stenciling agencies which require the application of paint, powder or the like, to be provided in addition to the 15 stencil and buffer.

I claim:

1. Means for ornamenting surfaces comprising a stencil plate of colored material capable of being abraded having a pattern cut 20 therein, and a buffer operable to abrade and remove particles of the material forming the

plate and to apply the same to the surface to be ornamented.

2. Means for ornamenting surfaces comprising a body the material comprising 25 which is capable of depositing coloring matter on a buffer, and a buffer adapted to contact with the said body.

3. A stencil having a body the material comprising which has the quality of depositing a coloring matter on a buffer when 30 said body is rubbed.

4. In an ornamenting device, a stencil, and a buffer impregnated with a coloring agent dislodged from the material forming the 35 stencil.

5. The herein described method of ornamenting surfaces, consisting in rubbing a stencil and transferring the material of the stencil to the surface to be ornamented.

HARRY CECIL MITCHELL.
